METHOD OF MAKING WELDED BLADE STRUCTURES

Robert C. Allen, Wauwatosa, Wis., assignor to
Allis-Chalmers Manufacturing Company, Mil-
waukee, Wis., a corporation of Delaware

Original application July 10, 1941, Serial No.
401,726. Divided and this application Febru-
ary 19, 1942, Serial No. 431,469

5 Claims. (Cl. 29—156.8)

This invention relates generally to elastic fluid turbines and more particularly to the manner and means for securing blades to a turbine disk or the like. The various features of construction, combinations of elements and arrangements of parts are claimed and also fully disclosed in application Serial No. 401,726, filed July 10, 1941, of which this application is a division.

An object of this invention is to provide an improved method of forming a blade assembly in which the blades are secured to a turbine disk or the like solely by weld metal.

Another object of this invention is to provide an improved method of forming a blade assembly in which blades having an approximately smooth base portion are rigidly secured to a turbine disk or the like presenting a similar peripheral surface.

Still another object of this invention is to provide an improved method of forming a blade assembly which is relatively inexpensive and which can be readily employed for reblading turbine rotors with a minimum of time and expense.

A further object of this invention is to provide an improved method of forming the improved blade assemblies hereinabove mentioned.

The invention accordingly consists of the method hereinafter more fully set forth in the appended claims and in the detailed description, in which:

Fig. 1 is a side elevation of a blade assembly embodying the invention;

Fig. 2 is a perspective view of the form of blade employed;

Figs. 3-6, inclusive, illustrate various stages in the construction of a blade assembly made in accordance with the invention; and

Fig. 7 is a section through a blade taken on line VII—VII of Fig. 5; and

Fig. 8 is a section through a series of blades taken on line VIII—VIII of Fig. 5.

Referring to the drawing, and particularly Figs. 1, 2, 6, 7 and 8, it is seen that the blade assembly 1, which represents a portion of a circumferential blade row, comprises a spindle or rotor disk member 2, a series of impulse type blades 3 having integral shroud and base portions 4 and 6, respectively, and weld metal 7 forming the sole connection between the base 6 of each blade 3 and the periphery of the disk 2. The shroud and base portions on adjacent blades are disposed in abutting relation (see Figs. 1 and 8) to form therebetween the fluid confining passages 8. The disk 2 and the blades 3 are preferably shaped to present a single surfaced periphery and single

surfaced base ends, respectively; i. e., a surface which is free of any projection or recess abruptly interrupting the continuity of the surface, and therefore the expression "single surface" as herein used includes surfaces which are either plane or curved, these surfaces being either perpendicular or oblique relative to the edges and to the side surfaces of a blade base or to the side surfaces of a spindle disk or the like, as this type of construction materially reduces costs.

The blade assemblies are preferably formed by placing a chill ring member 9 of inverted T-shape in cross section and the blades 3 on a suitable jig 11 (the particular form and the detailed construction of the jig are not essential features of this invention) and manipulating and clamping means 12 provided thereon to securely hold the blades 3 and the ring member 9 thereon in the relation shown whereupon the assembly comprising the jig 11, the blades 3 and ring member 9 is then associated with the disk 2 in the manner shown in Fig. 3 and secured in this position by any suitable means (not shown). The chill ring member 9 in addition to the usual functions of such members also acts to correctly position the blades 3 relative to the peripheral surface on the disk 2; i. e., the chill ring member 9 which preferably covers approximately one-half of the width of the peripheral surface on the disk 2 and which is engaged by a corresponding portion of the underside surface of the blade base 6, maintains the remaining portion of the underside surface of the blade base 6 disposed in spaced opposed relation with respect to the exposed portion of the peripheral surface on said disk thereby forming an upwardly opening channel or space 13. The next step (see Fig. 4) is to deposit the weld metal 7 in the circumferentially extending upwardly opening channel or space 13 which is defined by the exposed portion of the underside surface of the blade base 6, the exposed portion of the peripheral surface on the disk 2, and the adjacent edge of the chill ring member 9. The weld metal 7, which substantially fills the channel 13, securely unites the bases 6 of the blades 3 with the peripheral surface of the disk 2 and with the adjacent edge of the chill ring member 9; the weld metal fusing with the confining surface portions of the blade base 6, the chill ring 9 and the disk 2 to produce a bond of weld metal having the cross sectional configuration shown in Fig. 4. Next the clamping means 12 is released, the jig withdrawn and the chill ring member 9 removed by a suitable machining or grinding operation, which may be performed with the structure in

any desired position, to provide the circumferentially extending channel or space 14 shown in Fig. 5. In this connection, the cross sectional configuration of the channel 14 formed by the removal of the chill ring 9 is immaterial and may be formed with one beveled side wall surface as shown in Fig. 5 or otherwise shaped as necessitated by the tool selected for performing the machining or grinding operation. The channel 14 is then filled with weld metal 7 in accordance with the procedure described with respect to the channel 13 to provide the structure shown in Fig. 6. The remaining operations are to remove the excess weld metal in any suitable manner such as by machining or grinding and then to heat treat the entire assembly including the blading and spindle or rotor disk member to secure the requisite or desired physical properties.

The depositing of the weld metal in the channels 13 and 14 can be best effected with the structure positioned to place the channels on the upper side thereof, as indicated by Figs. 3 and 6 of the drawing, that is, with the assembly comprising the jig 11, the blades 3, the chill ring member 9 and the disk 2 associated as shown in Fig. 3, and after filling the channel 13 with weld metal and removing the jig 11 and chill ring 9 to produce the structure shown in Fig. 5, by then inverting said structure to place the channel 14 on the upper side thereof. However, it is not essential that the structure be positioned to place the channels 13 and 14 on the upper side thereof and depositing the weld metal therein, as weld metal can be readily deposited in said channels when placed in a horizontal position conforming with that effected by turning the structures shown in Figs. 3-5, inclusive, through an angle of 90°. Moreover, weld metal can also be deposited in an underside or downwardly opening channel similar to that presented by the structure when positioned as shown in Fig. 5, although this procedure (termed overhead welding) does require considerably more time and skill than is required when the channels are placed in either of the two positions hereinbefore specified. The correct welding procedure which may be effected with the channels placed in any of the positions herein specified can be readily determined by reference to part III of the Lincoln Electric Company's publication, "Procedure Handbook of Arc Welding Design and Practice," 1936.

It should be particularly noted that in the illustrated construction the area of the underside surface of the base 6 is considerably greater than the area of the blade cross section taken adjacent the base 6 as is clearly indicated by Fig. 7, and that therefore the effective bond area of the weld metal, which area is commensurate with the area of the underside surface of the blade base 6, is also materially greater than the area of the said blade section. In this connection, it is desirable although not essential in all instances to make the effective bond area of the weld metal, i. e., the cross sectional area of the weld metal taken on line A—A of Fig. 6, greater than the area of the cross section of the blade taken adjacent the base thereof.

The blades 3 are of milled construction and the abutting surfaces of the shroud and base portions on adjacent blades are finish machined to coat and provide in effect a sealed fluid confining passage 8. However, it should be understood that the blades 3 may be of any desired configuration and may be constructed or built-up in any desired manner, that the herein disclosed manner

and means for securing blades to a turbine disk or the like is of general application, and that therefore it is not desired to limit the invention to the exact details herein shown and described, as various modifications within the scope of the appended claims may occur to persons skilled in the art.

It is claimed and desired to secure by Letters Patent:

10. The method of making a bladed element for turbines and the like comprising providing an element with a single surfaced peripheral portion commensurate in width with the base ends of the blades to be attached thereto, providing blades having single surfaced base ends, partially covering said single surfaced peripheral portion with a plain chill ring structure, positioning and holding the blades in row forming relation with their base ends abutting and forming with said chill ring structure and with the exposed part of said peripheral portion, a first laterally opening channel, substantially filling said channel with metal fusibly integrally uniting the channel forming portions of said base ends, chill ring structure and peripheral portion, removing said chill ring structure to form a second laterally opening oppositely facing channel formed in part by the metal previously deposited in said first channel, and substantially filling said second channel with metal fusibly integrally uniting the exposed wall portions thereof.
20. The method of making a bladed element for turbines and the like comprising providing an element with a peripheral portion commensurate in width with the base ends of the blades to be attached thereto, providing blades having single surfaced base ends, partially covering said single surfaced peripheral portion with a structure presenting a substantially flat outer surface, positioning and holding the blades in row forming relation with their base ends abutting said substantially flat surface and forming with said structure and with the exposed part of said peripheral portion a first laterally opening channel, substantially filling said channel with metal fusibly integrally uniting the channel forming portions of said base ends, structure and peripheral portion, removing said structure to form a second laterally opening oppositely facing channel formed in part by the metal previously deposited in said first channel, and substantially filling said second channel with metal fusibly integrally uniting the exposed wall portions thereof.
30. The method of making a bladed element for turbines and the like comprising providing an element with a single surfaced peripheral portion commensurate in width with the base ends of the blades to be attached thereto, providing blades having single surfaced base ends, partially covering said single surfaced peripheral portion with a structure presenting a substantially flat outer surface, positioning and holding the blades in row forming relation with their base ends abutting said substantially flat surface and forming with said structure and with the exposed part of said peripheral portion a first laterally opening channel, substantially filling said channel with metal fusibly integrally uniting the channel forming portions of said base ends, structure and peripheral portion, removing said structure to form a second laterally opening oppositely facing channel formed in part by the metal previously deposited in said first channel, and substantially filling said second channel with metal fusibly integrally uniting the exposed wall portions thereof.
40. The method of making a bladed element for turbines and the like comprising providing an element with a peripheral portion commensurate in width with the base ends of the blades to be attached thereto, providing blades having single surfaced base ends, partially covering said single surfaced peripheral portion with a structure presenting a substantially flat outer surface, positioning and holding the blades in row forming relation with their base ends abutting said substantially flat surface and forming with said structure and with the exposed part of said peripheral portion a first laterally opening channel, substantially filling said channel with metal fusibly integrally uniting the channel forming portions of said base ends, structure and peripheral portion, removing said structure to form a second laterally opening oppositely facing channel formed in part by the metal previously deposited in said first channel, and substantially filling said second channel with metal fusibly integrally uniting the exposed wall portions thereof.
50. The method of making a bladed element for turbines and the like comprising providing an element with a single surfaced peripheral portion commensurate in width with the base ends of the blades to be attached thereto, providing blades having single surfaced base ends, positioning and holding the blades in row forming relation with their base ends opposing said single surfaced peripheral portion and in part spaced therefrom so as to form therewith a first laterally opening channel of less depth than the width of the base ends of said blades, substantially filling said channel with metal fusibly integrally uniting the opposed channel forming wall parts of said base ends and peripheral portion, forming between the remaining opposed parts of said base ends and peripheral portion, a second laterally opening oppositely facing channel having an inner wall portion formed in part by the metal previously deposited in said first channel, and substantially filling said second channel with metal fusibly integrally uniting the exposed wall portions thereof.
60. The method of making a bladed element for turbines and the like comprising providing an element with a single surfaced peripheral portion commensurate in width with the base ends of the blades to be attached thereto, providing blades having single surfaced base ends, positioning and holding the blades in row forming relation with their base ends opposing said single surfaced peripheral portion and in part spaced therefrom so as to form therewith a first laterally opening channel of less depth than the width of the base ends of said blades, substantially filling said channel with metal fusibly integrally uniting the opposed channel forming wall parts of said base ends and peripheral portion, forming between the remaining opposed parts of said base ends and peripheral portion, a second laterally opening oppositely facing channel having an inner wall portion formed in part by the metal previously deposited in said first channel, and substantially filling said second channel with metal fusibly integrally uniting the exposed wall portions thereof.
70. The method of making a bladed element for turbines and the like comprising providing an element with a single surfaced peripheral portion commensurate in width with the base ends of the blades to be attached thereto, providing blades having single surfaced base ends, positioning and holding the blades in row forming relation with their base ends opposing said single surfaced peripheral portion and in part spaced therefrom so as to form therewith a first laterally opening channel of less depth than the width of the base ends of said blades, substantially filling said channel with metal fusibly integrally uniting the opposed channel forming wall parts of said base ends and peripheral portion, forming between the remaining opposed parts of said base ends and peripheral portion, a second laterally opening oppositely facing channel having an inner wall portion formed in part by the metal previously deposited in said first channel, and substantially filling said second channel with metal fusibly integrally uniting the exposed wall portions thereof.
80. The method of making a bladed element for turbines and the like comprising providing an element with a single surfaced peripheral portion commensurate in width with the base ends of the blades to be attached thereto, providing blades having single surfaced base ends, positioning and holding the blades in row forming relation with their base ends opposing said single surfaced peripheral portion and in part spaced therefrom so as to form therewith a first laterally opening channel of less depth than the width of the base ends of said blades, substantially filling said channel with metal fusibly integrally uniting the opposed channel forming wall parts of said base ends and peripheral portion, forming between the remaining opposed parts of said base ends and peripheral portion, a second laterally opening oppositely facing channel having an inner wall portion formed in part by the metal previously deposited in said first channel, and substantially filling said second channel with metal fusibly integrally uniting the exposed wall portions thereof.
90. The method of making a bladed element for turbines and the like comprising providing an element with a single surfaced peripheral portion commensurate in width with the base ends of the blades to be attached thereto, providing blades having single surfaced base ends, positioning and holding the blades in row forming relation with their base ends opposing said single surfaced peripheral portion and in part spaced therefrom so as to form therewith a first laterally opening channel of less depth than the width of the base ends of said blades, substantially filling said channel with metal fusibly integrally uniting the opposed channel forming wall parts of said base ends and peripheral portion, forming between the remaining opposed parts of said base ends and peripheral portion, a second laterally opening oppositely facing channel having an inner wall portion formed in part by the metal previously deposited in said first channel, and substantially filling said second channel with metal fusibly integrally uniting the exposed wall portions thereof.

4. The method of making a bladed element for turbines and the like comprising providing an element with a single surfaced peripheral portion commensurate in width with the base ends of the blades to be attached thereto, providing blades adapted to be positioned in row forming relation with their base ends opposing the peripheral portion of said element, positioning and holding the blades in row forming relation with portions of their base ends spacedly opposing and forming with a part of said peripheral portion, a first laterally opening channel of less depth than the width of the base ends of said blade, substantially filling said channel with metal fusibly integrally uniting the opposed channel parts of said base ends and peripheral portion, forming between the remaining opposed portions of said base ends and peripheral portion, a second laterally opening oppositely facing channel formed in part by the metal previously deposited in said first channel, and substantially filling said second channel with metal fusibly integrally uniting the walls defining same.

5. The method of making a bladed element for turbines and the like comprising providing an element with a peripheral portion commensurate in width with the base ends of the blades to be attached thereto, providing blades having single surfaced base ends, positioning and holding the blades in row forming relation with portions of their base ends spacedly opposing and forming with a part of said peripheral portion a first laterally opening channel of less depth than the width of the base ends of said blades, substantially filling said channel with metal fusibly integrally uniting the opposed channel forming parts of said base ends and peripheral portion, forming between the remaining opposed portions of said base ends and peripheral portion, a second laterally opening oppositely facing channel formed in part by the metal previously deposited in said first channel, and substantially filling said second channel with metal fusibly integrally uniting the walls defining same.

ROBERT C. ALLEN.
